CLAIM

The ornamental design for garden tool as shown and described.

DESCRIPTION

FIG. 1 is a perspective view of garden tool according to a First Embodiment our new design;

FIG. 2 is an alternate perspective view thereof;

FIG. 3 is an alternate perspective view thereof;

FIG. 4 is an alternate perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof;

FIG. 10 is a bottom plan view thereof;

FIG. 11 is a perspective exploded view thereof;

FIG. 12 is a perspective exploded view thereof;

FIG. 13 is a perspective view of garden tool according to a Second Embodiment our new design;

FIG. 14 is an alternate perspective view thereof;

FIG. 15 is an alternate perspective view thereof;

FIG. 16 is an alternate perspective view thereof;

FIG. 17 is a front elevation view thereof;

FIG. 18 is a rear elevation view thereof;

FIG. 19 is a left-side elevation view thereof;

FIG. 20 is a right-side elevation view thereof;

FIG. 21 is a top plan view thereof;

FIG. 22 is a bottom plan view thereof;

FIG. 23 is a perspective exploded view thereof; and,

FIG. 24 is a perspective exploded view thereof.

The broken lines shown in the drawings depict portions of the garden tool that form no part of the claimed design.
